UNITED STATES PATENT OFFICE.

HARRY S. HART, OF CHICAGO, ILLINOIS.

DUMP CAR.

Application filed August 4, 1921. Serial No. 489,700.

To all whom it may concern:

Be it known that I, HARRY S. HART, a citizen of the United States, residing at Chicago, in the county of Cook and State 5 of Illinois, have invented certain new and useful Improvements in Dump Cars, of which the following is a specification.

This invention relates to a new and improved dump car construction, and more 10 particularly to a hopper car design particularly adapted for use in reconstructing existing hopper cars.

As is well known, hopper cars generally used for carrying coal are commonly built 15 with sloping end portions, sloping downwardly from a point near the upper portion of the end of the car to a point within the trucks, the floor of the intermediate portion of the car being comprised of hoppers, 20 either longitudinally or transversely arranged as the case may be.

This construction obviously does not take full advantage of the maximum capacity as if it were possible to use the entire space 25 enclosed by the sides and ends of the car for load carrying. As a means for taking advantage of the entire load carrying capacity of such cars, I have devised various improvements in such cars, an example being 30 shown in my prior Patent No. 1,304,969, granted May 27th, 1919, which avoid the loss of space in constructing new cars.

It is highly desirable that the large number of cars now in use built upon the old 35 uneconomical design should be reconstructed so as to increase the carrying capacity without increasing the other over all dimensions.

It is an object of the present invention to 40 provide a new and improved car design adapted to secure the maximum possible carrying capacity.

It is a further object to provide such a design which is especially adapted for use 45 in reconstructing existing hopper cars.

It is an additional object to provide a reconstruction design which involves the minimum amount of change in existing 50 cars, combined with securing the maximum possible carrying capacity.

Other and further objects will appear as the description proceeds.

In carrying out my invention, I provide a car having vertical sides and ends, the 55 floor portion at the ends comprising—as shown in the present embodiment of my in-

vention—downwardly and outwardly sloping sections, extending inwardly from the ends of the car toward the center of the car. These sloping floor sections, however, 60 instead of extending approximately over the trucks for their full length, as shown in my prior patents, an example of which is above referred to, extend to the bolsters only, the remainder of the floor comprising hopper portions which may be of well known types. In illustrating the invention, I have selected a well known type of car having transverse hoppers between the trucks illustrating my improvement as applied to such a car. It will be understood, 70 however, that my invention is equally applicable to hopper cars of other types.

The sloping hopper floors of such existing hopper cars are commonly supported above 75 the body bolsters by cross beams extending from the bolsters to the car floor. Broadly, my invention consists in a car with which the sloping floor stops at the point of support by these cross beams. Between this point 80 and the end of the car a floor is provided sloping downwardly toward the sides of the car. Doors upon the side of the car are provided for permitting the discharge of material carried in these end portions. 85 This construction is particularly adapted for reconstruction purposes, since it is only necessary to cut off the existing sloping floor beyond the connection to the cross beam end to add the new end floors and doors. The cross beam and other supporting elements 90 of the sloping floor need not be modified in any way.

I have illustrated a preferred embodiment 95 of my invention in the accompanying drawings, in which—

Figure 1 is a plan view of one half of a hopper car according to my design;

Figure 2 is a longitudinal section of Figure 1; and

Figure 3 is a transverse section of the car, the right hand half of the section being taken on line A—A of Figure 2 and the left hand half being taken on line B—B of Figure 2.

As shown in the drawings, the car comprises the sides 5, ends 6, center A-portion 7, transverse hopper doors 8 and sloping hopper floor 9. The transverse doors 8 are operated by suitable mechanism 10. The body bolsters 11 are located at either end above the trucks and extending above these

bolsters are the cross beams 12, the upper edges of which are secured at 13 to the hopper floor 9.

- Between the end of the sloping hopper floor 13 and the end of the car 6 a floor 14 is provided having downwardly sloping portions 15, these portions 15 being adapted to discharge through doors 16, which doors are operated by the usual mechanism 17.
- 5 10 In reconstructing existing cars to conform to the present design, the floor 9 is cut off at the point 13 in an approximately straight line transversely of the car and the additional floor portions 15 are riveted in place.
- 15 20 The doors 16 are added together with their operating mechanism. As has been stated, no change in the body bolster, cross beam or remainder of the floor 9, is required. This permits change of existing cars at comparatively small expense.

It will be apparent from consideration of the drawings, especially Figures 2 and 3, that a very material increase in car carrying capacity is secured. At the same time 25 a clean dumping car is maintained, part of the dump being between the tracks and the dump of the portions over the trucks being outside the tracks.

I claim:

- 30 1. A dump car having sides, ends and a floor, the floor portions intermediate the car trucks comprising hoppers having floors sloping downwardly from the trucks, said floor portions terminating above the trucks in lines transverse of the car, and downwardly extending vertical walls on such lines, the remainder of the floor between said lines and the ends of the car being located below the plane of said floor portions.
- 35 40 2. A dump car having sides, ends and a floor, the floor portions intermediate the car trucks comprising hoppers having floors

sloping downwardly from the trucks, said floor portions terminating above the trucks in a substantially straight line transverse of 45 the car, and the remainder of the floor between said lines and the ends of the car sloping outwardly and downwardly toward the sides of the car.

3. A dump car having sides, ends and a 50 floor, the floor portions intermediate the car trucks comprising hoppers having floors sloping downwardly from the trucks, said floor portions terminating above the trucks upon the lines where the supporting cross beams are secured to said sloping floors, and downwardly extending vertical walls on such lines, the remainder of the floor between 55 said lines and the ends of the car being located below the plane of said floor 60 portions.

4. A dump car having sides, ends and a 65 floor, the floor portions intermediate the car trucks comprising hoppers having floors sloping downwardly from the trucks, said floor portions terminating above the trucks upon the lines where the supporting cross beams are secured to said sloping floors, and the remainder of the floor between 70 said lines and the ends of the car sloping outwardly and downwardly toward the sides of the car.

5. A dump car having sides, ends and a 75 floor, the floor portions intermediate the car trucks comprising hoppers having floors sloping downwardly from the trucks, said floor portions terminating above the trucks in a substantially straight line transverse of the car, the remainder of the floor between 80 said lines and the ends of the car being arranged to discharge the load outwardly toward the sides of the car.

Signed at Chicago, Illinois, this 26th day of July, 1921.

HARRY S. HART.
